(57) **CLAIM**

The ornamental design for an automobile gauge mount, as shown and described.

DESCRIPTION

FIG. 1 is a front perspective view of an automobile gauge mount showing our new design;

FIG. 2 is a front view thereof;

FIG. 3 is a rear view thereof;

FIG. 4 is a left side view thereof;

FIG. 5 is a right side view thereof; and,

FIG. 6 is a top view thereof, whereby the bottom view is a mirror image thereto.

The broken lines in the views show environmental features which are for illustrative purposes only and form no part of the claimed invention.
